UNITED STATES PATENT OFFICE.

JOHN W. MEAKER, OF DETROIT, MICHIGAN.

SPARK-PLUG.

1,156,797.

Specification of Letters Patent. Patented Oct. 12, 1915.

Application filed January 2, 1913. Serial No. 739,908.

To all whom it may concern:

Be it known that I, JOHN W. MEAKER, a citizen of the United States of America, residing at Detroit, in the county of Wayne, 5 and State of Michigan, have invented certain new and useful Improvements in Spark-Plugs, of which the following is a specification, reference being had therein to the accompanying drawings.

10 In a construction of spark plugs for explosive engines that are subjected to rough usage, as on automobiles or the like, it is desirable that the body of the plug, ordinarily of porcelain or other frangible vitreous material, be as large as possible to lessen the liability of breakage. It is also desirable, inasmuch as the plugs are made in large quantities, that the mechanical construction be simplified to reduce the cost 15 of manufacture without impairing the efficiency.

This invention relates to spark plugs and to an arrangement thereof whereby the body of the plug is not liable to fracture and 20 whereby the parts are readily machined and assembled. The invention also includes a disposition of the ignition terminals or spark points which minimizes the accumulation of soot and dirt thereon.

25 The invention consists in the matters hereinafter set forth and pointed out in the appended claims.

In the drawings, Figure 1 is a view, partially in elevation and partially in longitudinal section, of one type of spark plug that embodies features of the invention; Fig. 2 is a bottom plan view of the plug; Fig. 3 is a view showing a modification of the lower part or nipple of the plug; Fig. 4 is a view 30 showing a further modification; Fig. 5 is a view in detail showing a spark plug with one part omitted; and Figs. 6, 7 and 8 are views in detail showing one form of spark terminals.

35 As herein shown, an outer casing 1 is internally screw-threaded to receive a stop collar 2 that is thereby adjustably positioned longitudinally in the casing. A body of porcelain or refractory insulating material 40 has an enlarged central portion 3 and tapered depending portion 4, the body being secured in position by an annular bushing 5 forcing the portion 3 to seat against the stop collar 2. Suitable packing rings 6 are interposed to afford a tight joint. The upper portion 7 of the body is as large as the bush- 45

ing 5 will permit and is provided with the usual cap 8. The casing 1 is secured in position by a screwthreaded nipple 9 that is turned to seat against the under side of the stop collar 2. The lower portion of the nipple is slotted or otherwise arranged for the convenient application of a turning tool or wrench and is provided with sparking terminals to coact with a stem 10 in the body. 50 These terminals as shown in Fig. 1, comprise a pair of parallel loops 11 with inclined body portions so that lubricant lodging thereon runs to the lower bend or corner and drops off without interfering with the spark gaps. Or, as indicated in Figs. 6, 7 and 8, the terminals may take the form of a corrugated wire 12 secured on an end flange 13 of the nipple by peening over a shoulder shown at 14, and arranged to coact with a 55 suitable head 15 on the body stem. Preferably the head is formed of a sheet metal blank drawn and slotted as shown that is fixed to the stem head. The shape of the corrugated wire prevents the lodging of soot 60 thereon and by bending the loops downwardly, adjustment is afforded to get the desired interval between the center terminal and loops. The loops may be formed, however, separable or otherwise, and may be secured in any suitable manner.

The collar 2 shown in Fig. 1 may be replaced by a ring 17 as indicated in Fig. 4 with an additional packing ring 18, against which the nipple bears. Or the collar may 70 be entirely omitted as indicated in Fig. 5, in which instance a nipple 19 is provided to bear upwardly against a suitable packing ring 20 and a lower shoulder of the central 75 portion 3 of the body.

In either form of construction space is afforded for a body having a large cross sectional area which reduces liability of fracture while the parts that support the body are readily assembled and are machined with 80 a minimum number of steps.

The exterior or projecting portion of the nipple may have the same diameter and thread as the portion inserted in the body, 85 or it may have a different diameter and be provided with screwthreads of any pitch. This enables the plug as a whole to be readily adapted for use with any make of motor, as the nipple is easily designed to 90 meet a special requirement without altering 95 the body or casing of the nipple.

Obviously changes in the details of con-

22
struction may be made without departing from the spirit of my invention and I do not care to limit myself to any particular form or arrangement of parts.

5 What I claim is:—

1. A spark plug comprising an interiorly screwthreaded casing, an exteriorly screwthreaded nipple in engagement with said casing and protruding from the lower end thereof and adapted to be limited in its movement relatively to said casing and provided with a spark terminal near the outer end, a body of insulating material having an intermediate enlarged portion in the casing 15 and carrying a terminal stem co-acting with the nipple terminal, a packing member between the inner end of the nipple and the enlarged portion of the body, and a bushing in screwthreaded engagement with the casing 20 encircling the body and forcing the latter against the packing ring and toward the nipple end.
2. A spark plug comprising an interiorly

screwthreaded casing, an exteriorly screwthreaded nipple in engagement with said casing protruding from the lower end thereof and having a spark terminal near the outer end, means within the casing forming a shoulder for limiting the movement of the nipple relatively to the casing, a body of insulating material having an intermediate enlarged portion in the casing and carrying a terminal stem co-acting with the nipple terminal, packing between the inner end of the nipple and the enlarged portion of the body, and a bushing engaging the casing and encircling the body for forcing the latter against the packing ring toward the nipple end.

In testimony whereof I affix my signature 40 in presence of two witnesses.

JOHN W. MEAKER.
